UNITED STATES PATENT OFFICE.

FITZ WILLIAM SARGENT, OF MAHWAH, NEW JERSEY, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,158,562.

Specification of Letters Patent.

Patented Nov. 2, 1915.

Application filed August 24, 1915. Serial No. 47,045.

To all whom it may concern:

Be it known that I, FITZ WILLIAM SARGENT, a citizen of the United States, and a resident of Mahwah, in the county of Bergen and State of New Jersey, have made and invented certain new and useful Improvements in Brake-Shoes, of which the following is a specification.

This invention relates to brake shoes and 10 concerns in particular the reinforcing back therefor, the object of the present invention being to prevent the opening up of the lug and the spreading of the back, should the body of the shoe become broken in service at 15 points between the spaced sides of the lug.

It has been found in practice that a reinforcing back for brake shoes, which is provided with an outwardly looped integral lug, is liable to spread and the sides of the 20 lug to open up should the body of the shoe become broken and fractured at points between the sides of the lug, as very often happens. This fracturing and breaking of the body of the shoe beneath the lug is particularly liable to occur, as there is no reinforcement for this portion of the shoe body; and, furthermore, when the body of the 25 shoe does become fractured and broken at these points, the fragments become detached 30 and separated and fall away from the shoe. In order, therefore, to reinforce this central portion of the shoe which lies beneath the open extremity of the lug, and to prevent the detachment of the fragments and the 35 opening up of the sides of the lug, and the corresponding spreading of the back, I provide a tie-plate or plates formed integral with the back and extending across and beneath the lug, and of such shape or form that they 40 become securely anchored within the cast metal of the body of the shoe, and the further or additional fixation and securing thereof is rendered unnecessary.

Other objects and advantages will appear 45 as the description proceeds, wherein it is to be understood that changes in the precise embodiment of the invention can be made within the scope of what is claimed without departing from the spirit thereof.

The preferred embodiment of my invention is disclosed in the accompanying drawings, wherein:—

Figure 1 is a view in plan of a blank from 55 which my improved reinforcing back is formed. Fig. 2 is a view in side elevation

of the finished back and illustrating by dotted lines the manner in which the tie-plates are bent beneath the lug. Fig. 3 is a view in longitudinal vertical section of a brake shoe having embodied therein a reinforcing back 60 possessing the characteristic features of my invention. Fig. 4 is a view in transverse section taken on the line 4—4 of Fig. 3. Fig. 5 is a view in perspective of a slightly modified form of reinforcing back.

Referring specifically to the several views, the blank disclosed in Fig. 1 includes the oblong plate or body 5, the central and lug forming portion 6 of which is provided with the key openings 7. Arranged upon opposite sides of the key openings 7 are the confronting and U-shaped slits 8, which define the tongues 9. These tongues widen toward their free extremities, and are arranged upon opposite sides of the longitudinal medial line of the body 5. The blank further includes a number of openings 10 arranged to the sides of the tongues 9, which are adapted to receive the molten metal of the cast body of the shoe therein and increase 65 the anchorage therefor. The blank is somewhat greater in length than that of the finished back, and is outwardly looped at its central portion so as to form the integral and looped lug 11, the openings 7 in which 70 are adapted to receive the shoe-attaching key. The tongues 9 are bent beneath the back, as illustrated by the dotted lines in Fig. 2, and upwardly into contact with the lower surface thereof, so as to define tie-plates 12, the same extending across and beyond the sides of the looped integral lug. The tongues 9 being disposed upon opposite 75 sides of the longitudinal medial line of the blank provide that the tie-plates 12 will be arranged side by side and spaced a slight 80 distance apart, as illustrated in Fig. 4.

The reinforcing back, as thus constituted, is placed within a suitable mold, and the body 13 of the shoe cast thereupon, the molten metal of which extends within the openings 14 formed by removal of the tie-plates 12. The molten metal also flows up within and becomes anchored to the side walls of the openings 10, resulting in the 85 secure anchorage of the body of the shoe to the reinforcing back.

The widening or beveled tie-plates extending, as they do, in opposite directions across 90 and beyond the open portion of the lug, be- 95

come securely anchored within the cast body of the shoe, and prevent the opening up of the lug and the spreading of the back, even though the body of the shoe should become 5 broken and fractured at points between the sides of the lug. In addition to this holding action of the tie-plates, they further reinforce the central portion of the body of the shoe which lies beneath the lug 11, and 10 which portion is necessarily exposed to the greatest strains.

The modified form of back illustrated in Fig. 5 is similar to the foregoing, with the exception that but a single tie-plate 12' is 15 provided. This tie-plate widens toward its free extremity and is accordingly anchored to the cast metal of the body of the shoe, in a manner similar to that of the tie-plates above described.

20 What I claim is:—

1. A blank of the class described comprising a body with a lug forming portion and with U-shaped slits defining tongues, said tongues arranged upon opposite sides of 25 said lug forming portion, and upon opposite sides of the longitudinal medial line of said body, said tongues widening toward their free extremities.
2. A back for brake shoes with a looped lug, a tie-plate projecting across the open extremity of said lug and widening toward one of its ends.
3. A back for brake shoes with a looped lug, and having a tie-plate formed integral 35 therewith and projecting across the open extremity of said lug and widening toward its free end.

4. A back for brake shoes with a looped lug and with integral tie-plates extending in opposite directions across said lug. 40

5. A back for brake shoes with a looped lug and with integral tie-plates extending in opposite directions across said lug, said tie-plates widening toward their free extremities. 45

6. A brake shoe comprising a reinforcing back with a lug, a tie-plate formed integral with said back and projecting across the open extremity of said lug, and a wearing body anchored to and reinforced by said lug 50 and said tie-plate.

7. A brake shoe comprising a reinforcing back with a lug, a tie-plate formed integral with said back and projecting across the open extremity of said lug, said tie-plate 55 widening toward its free extremity, and a wearing body anchored to and reinforced by said back and said tie-plate.

8. A brake shoe comprising a back with an integral lug, and tie-plates formed integral with said back and extending in opposite directions across and beyond the open extremity of said lug, said tie-plates arranged side by side and widening toward 60 their free extremities, and a wearing body 65 anchored to said back and tie-plates.

Signed at Mahwah, in the county of Bergen and State of New Jersey this 20th day of August A. D. 1915.

FITZ WILLIAM SARGENT.
